OF NEW JERSEY

ELECTRODYNAMIC SOUND RECORDER AND REPRODUCER

Application filed September 24, 1928. Serial No. 307,949.

The present invention relates to sound recorders and reproducers, and particularly to those of the electro-dynamic type.

Among the objects of the invention is to provide a novel electrical device capable of converting mechanical movements and energies into electrical effects and vice versa for sound recording and sound reproduction, the device operating as a motor when recording and as a generator when reproducing.

In a preferred embodiment, the device comprises balanced conductors movable in plural gaps for multiplied energy conversion. The coils preferably move in opposite directions, such that as one coil is moving into a stronger part of the field, the other coil moves into a weaker part of the field with a resultant compensation and average constant current. The output follows more nearly a sine curve.

Another object of the invention is to provide for small movements of the coils, such that, as for example, where two coils are used with half the leverage of a single coil having twice the movement, the shorter movements are much closer to a linear movement in cutting the magnetic lines than would be the case of the larger movement of a single coil designed for the same energy conversion. The lateral component of movement of two coils having but a small arc movement, as for example a few degrees, will be negligible or practically nil. Yet, if a single coil be given twice the leverage to get the same energy conversion, twice the arc movement at least, is required, but the lateral component movement will be very much more than twice that in the case of half the angular movement which is necessary for the two coils of half the leverage. The use of multiple coils, connected in series, with fractional leverage produces a much more efficient energy conversion approaching more closely to perfect sine curves. This reduces practically all liability of mechanical resonance of parts. Other advantages are also gained, such as making for a more rigid and stronger structure, a more compact device; less inertia of mass or momentum to overcome, and the like.

Other objects, capabilities, advantages and features are comprehended by the invention

as will later appear and as are inherently possessed thereby.

Referring to the drawings:

Fig. 1 is a sectional view taken in a plane represented by line 1—1 in Fig. 2 of the drawings. 55

Fig. 2 is a sectional view taken in a plane represented by line 2—2 in Fig. 1 of the drawings.

Fig. 3 is a sectional view taken in a plane represented by line 3—3 in Fig. 1 of the drawings. 60

Fig. 4 is a plan view of the lever used in an illustrative embodiment of the invention, and

Fig. 5 is a detail sectional view, enlarged, 65 of a part of the device.

Referring now more in detail to the drawings, the embodiment selected to illustrate the invention is shown in connection with housing 1 having a back plate 2 with which is rigidly connected a connector 3 adapted in any suitable manner for connection with a goose-neck of a tone arm of a phonograph or the like, so that it may act as an electrical reproducer or pick-up device, although it is to be understood that this is merely illustrative, and that the device is designed to operate for recording when electrical energies produced from sound, act upon or through a recording or engraving stylus. 70

Within the housing is a magnet 4, which may be of the permanent magnet type, if desired, or of the electro-magnetic type, in which case it may have an energizing coil 5. In the form of device chosen to illustrate the invention, the magnet 4 is supported by a non-magnetic plate 6 having a flange 7 by which it is secured to the back 2 of the housing, as by soldering or by screws 8 threaded into an insulating block 9, or both, as desired. The plate 6 has apertures through which the ends of the magnet 4 protrude to provide poles 10 and 11. Secured to the underside of plate 6, as by securing elements 6^a, is a magnetic cross piece 12 having an annular pole shoes or pieces 13 and 14 at its ends, the shoes surrounding the poles 10 and 11 and having apertures of a size to provide annular magnetic gaps 15 and 16 between said shoes and the poles 10 and 11. 85 90 95 100

The non-magnetic member 6 has side portions provided with depending lugs 19 and 20 carrying pivot screws 21 and 22 adapted to rotatably support a pivot shaft 22^a to which is secured a lever 23 having two oppositely extending short arms 24 and 25, and a depending arm 26 acting as a carrier for a stylus 27 of either the recording or reproducing type. The lever 23 is of open structure and made of light weight metal such as aluminum. It has side pieces 17 and 18 acting as stays or strengthening elements. The stylus may be held secured in the socket of the arm 26 by a thumb screw 28 or the like. 15 A record or matrix 29 is shown in association with the stylus.

At the ends of the arms 24 and 25 are provided annular parts or rings 30 and 31 with which are connected tubular elements 20 32 and 33 of thin insulating material, these tubes being very light in weight and serving as spools for windings or coils 34 and 35 of very fine wire. These coils are located in the air or magnetic gaps 15 and 16, and co-axial 25 with the poles 10 and 11 and the shoes 13 and 14, and are also preferably connected in series by a wire 36 passing through suitable apertures provided in the rings 30 and 31 and in arm 26. The other ends of the coils 34 and 30 35 have leads 37 and 38 running to binding screws 39 and 40 secured to the insulating block 9 and also acting to bind conducting elements 41 and 42 connected to binding 35 screws 43 and 44 also secured to the insulating block 9. From the latter binding screws 43 and 44 may run suitable leads to an electrical amplifying device, such as power amplifiers used in radio sets or the like, when the device is used as a reproducer or pick-up 40 attachment, or the leads may run to an electrical apparatus for converting sound vibrations into electrical energy, in which case the device acts as a recorder for producing sound undulations in the matrix 29. When using 45 an electro-magnet, the coil 5 may be energized from any suitable electrical source.

For the purpose of normally holding the lever 23 and connected parts in balanced or mid-position, or to bring the same back to such position when it has been moved, suitable resilient or similar members 45 and 46, such as felt, rubber or like pads, are interposed between the upper parts of the arms 24 and 25 and the lower face of the magnetic member 12, as clearly shown in Fig. 1 of the drawings.

In operation the magnet 4 and cross piece 12 with shoes 13 and 14 form a magnetic circuit for magnetic flux, the latter forming a flux field or magnetic lines in the gaps 15 and 16, these lines being substantially at right angles to the axes of the poles 10 and 11. The lever 23 vibrates about the axis of pivot 22^a to cause the coils 34 and 35 to move in the gaps 15 and 16 with the convolutions of

the coils transversely of the lines of force of the magnetic field in the gaps, this cutting such lines. Inasmuch as the lever arms 24 and 25 are short, the movements of the coils 34 and 35 in the gaps 15 and 16 are practically lineal and co-axial with the axes of the poles 10 and 11. 70

In the case of the stylus operating in a groove of a record 29, the mechanical vibrations of the stylus are imparted in the lever 23 for moving the coils in the gaps and the cutting of the lines of force causes a consonant variation in the circuit of the coils and the amplifying device, the device of this invention acting, in such case, as an electrical sound reproducer. When this device is to operate as a recorder, the electrical energy from a conversion apparatus varies in the circuit of the coil to cause them to move or operate as a motor to effect a vibration of the lever 23 and engraving stylus 27 for producing a sound groove in a matrix 29. 80

It will be noted that by using a pair of balanced coils at the ends of a first class lever, one coil will be moving in an opposite direction to the other, such that as a coil is moving into a strong field the other will be moving into a weak field, so that the resultant effect is an average constant force, whether mechanical or electrical depending upon the 90 direction of conversion from electrical to mechanical or from mechanical to electrical energies.

While I have herein described and upon the drawing shown a specific embodiment 100 illustrative of the invention, it is to be understood that the invention comprehends other structures, constructions, arrangements of parts, details and features, without departing from the spirit thereof. 105

Having thus disclosed the invention, I claim:

1. A dynamic recorder and reproducer, comprising magnets having gaps, generating conductors in said gaps, said conductors being spaced and having axes, a vibratile member carrying said conductors for vibration of the conductors transversely to the magnetic flux in said gaps and along said axes, and means for vibratably supporting 115 said member.

2. A dynamic recorder and reproducer, comprising magnets having gaps, generating conductors in said gaps, a vibratile member carrying said conductors for vibration of the conductors in opposite directions and transversely to the magnetic flux in said gaps, and means between said conductors for vibratably supporting said member. 120

3. A dynamic recorder and reproducer, comprising magnetic elements having magnetic gaps, an elongated supporting member, generating conductors carried at the ends of said member and located in said gaps, said conductors being spaced and having different 125 130

axes, means intermediate the ends of said member for oscillatably supporting said member whereby said conductors move in said gaps along said axes and across the flux lines therein.

4. A dynamic recorder and reproducer, comprising magnetic elements having magnetic gaps, an elongated supporting member, generating conductors carried at the ends of said member and located in said gaps, fulcrum means at an intermediate part of said member for oscillatably supporting said member, and a stylus associated with said member.

15 5. An electrical recorder and reproducer, comprising magnetic poles having air gaps, coils in said gaps, a support for the coils, and means for oscillatably supporting the support whereby the coils may move in said gaps, and a stylus associated with said support.

20 6. An electrical recorder and reproducer, comprising magnetic poles having air gaps, coils in said gaps, a support for the coils, and means for oscillatably supporting the support whereby the coils may move in said gaps, and a stylus associated with said support, the center of oscillation being located between said coils whereby the coils oscillate in opposite directions.

25 7. An electrical recorder and reproducer, comprising spaced magnetic gap means, coils adapted to move in the gaps of said means transversely to the magnetic flux in said gaps, a supporting member for said coils, means for oscillatably supporting said supporting member whereby said coils move in opposite directions, and a stylus associated with the supporting member.

40 8. A dynamic recorder and reproducer, comprising magnetic members arranged in a magnetic circuit and being provided with a pair of spaced magnetic gaps, a lever fulcrumed between said gaps and having arms extending to said gaps, generating coils in said gaps and carried by said arms, a stylus associated with said lever and adapted to vibrate with said lever to cause said coils to vibrate in said gaps across the flux therein and in opposite directions.

45 9. A dynamic recorder and reproducer, comprising a magnet having spaced poles, a pole shoe for each pole and spaced therefrom to provide an annular gap between the shoe and the pole, a lever fulcrumed between said poles and having short arms extending to said gaps, coils carried at the opposite ends of said lever and located in said gaps, and a stylus connected to said lever and vibratable therewith for moving the coils in said gaps in axial directions and with opposite movements for an average constant current conversion in the coils.

50 10. A dynamic recorder and reproducer, comprising spaced magnetic poles and pole

pieces providing magnetic gaps therebetween, a lever having its axis between said gaps and substantially in the plane of said gaps, said lever having arms in said plane, coils at the ends of said arms and in said gaps, said lever having a third arm transverse to said plane, and a stylus carried by said third arm, said lever when vibrated adapted to move said coils to cut the magnetic flux in said gaps.

75 In witness whereof, I hereunto subscribe my name to this specification.
